UNITED STATES PATENT OFFICE.

FREDERICK A. HART, OF NEW BRITAIN, CONNECTICUT, ASSIGNOR TO REMINGTON TYPEWRITER COMPANY, OF ILION, NEW YORK, A CORPORATION OF NEW YORK.

TYPEWRITING MACHINE.

Application filed October 5, 1923. Serial No. 686,698.

To all whom it may concern:

Be it known that I, FREDERICK A. HART, citizen of the United States, and resident of New Britain, in the county of Hartford and State of Connecticut, have invented certain new and useful Improvements in Typewriting Machines, of which the following is a specification.

My invention relates generally to paper feeding and controlling mechanism for typewriting machines, and its chief object is to provide new and improved mechanism of the character stated. More specifically the object of the invention is the provision of what is termed platen sweep mechanism which is particularly adapted for condensed record billing where there may be employed bill sheets having headings of different widths, varying from comparatively short headings to headings of great depth.

To the above and other ends which will hereinafter appear, my invention consists in the features of construction, combinations of devices and arrangements of parts hereinafter described and particularly pointed out in the claims.

In carrying out the preferred form of my invention, means are provided for continuously turning the platen, or "sweeping" it as it is sometimes termed, to predetermined extents both forward and backward, devices being employed for limiting the backward sweep to two less units of line space distance than the forward sweep, in order that the condensed record sheet remaining in the machine may be automatically positioned without care on the part of the operator, for proper co-operation with each fresh bill sheet that is inserted and brought by the forward sweep of the platen into position for receiving the first line of writing under the heading on the bill sheet.

My invention will be described in detail in relation to the accompanying drawings, wherein—

Figure 1 is a fragmentary end view of the carriage and platen of a #11 Remington typewriting machine embodying my invention.

Figures 2, 3 and 4 are diagrammatic end views partly in section illustrating different steps in the platen sweep operation.

Figure 5 is a sectional view drawn to an enlarged scale, the plane of the section being indicated by the section line 1—1 in Fig-

ure 1 and looking in the direction of the arrows at said line.

Figure 6 is a perspective view illustrating different parts constituting a novel platen sweep mechanism, the parts being spread or separated for the sake of clearness.

The carriage of the #11 Remington typewriting machine comprises a truck and a platen frame, which latter is shiftably mounted on the truck. For present purposes, however, applicant while employing the usual truck and platen frame, screws down the shift stops as is sometimes done, so as to prevent the frame from shifting on the truck, and also employs at the right-hand end an additional bracket or end bar which is secured rigidly to the platen frame and is adapted to provide a support for certain novel parts hereinafter described. The top plate 1 of the main frame of the machine supports front and rear guide rails, the rear rail 2 being shown herein. Said guide rails co-operate through antifriction rollers 3 with the grooved rear bar 4 of a rectangular truck. Said truck further comprises end bars 5 which connect the rear bar with a similarly grooved front bar that also co-operates through antifriction rollers with the front trackway, said trackway however, together with the front bar and the co-operating rollers being omitted from the drawing. The end bars 5 are formed with eye portions or perforated enlargements 6 to afford passage-way for the platen axles, and threaded into the top and bottom of each enlargement is a stop screw 7 having a check nut 8. The platen frame comprises end bars 9 connected by a transverse channel bar 10 underlying the platen and also by a cross rod 11, which cross rod connects the rear upper end portions of the bars 9. Links 12 connect the end bars 9 with the truck. Supported on the platen frame and truck is a cylindrical platen 13 provided at its right-hand end with a line spacing ratchet wheel 14 with which co-operates the spring roller detent 13^a. The usual front and back feed rollers are conventionally shown, and are designated as 15. The left-hand mounting of the platen is of ordinary construction. At its right-hand end a cover plate or head 16 is arranged outside the ratchet wheel 14 and is provided with a lug 17 which engages a recess or notch 14^a in the ratchet wheel 14. Threaded into the plate 16 is the left-hand

100
105
110

end portion of an outwardly extending sleeve or tube 18. Slidably supported in the bore of the sleeve 18 is a stub shaft 19 provided at its outer end with the usual finger wheel 20, the inner end of said shaft being formed with a notch 21 which receives the flattened end portion or tongue 22 of a release rod 23 adapted to release the clutch devices whereby the ratchet wheel 14 is normally clutched to the platen, the unclutching operation being effected by pushing in the finger wheel 20 and causing the shaft 19 to force in the release rod 23. Ordinarily, when the finger wheel is turned the platen is turned also by reason of the connection 21, 22 between the rods or shafts 19 and 23. This construction also affords a ready detachment of the platen while leaving the stub shaft 19 in the platen frame. Step by step line spacing movements are communicated to the platen by the usual devices co-operating with the ratchet wheel 14, said devices as shown in Fig. 1 comprising a line spacing pawl 24, pivoted at 25 on a rotary carrier 26 mounted concentrically with the platen. Pivots connected to the pawl 24 is the rear end of a push link 24^a which is connected by devices, not shown, with the usual line spacing handle mounted on the right-hand end bar 6 of the truck. The pawl 24 is normally disengaged from the ratchet wheel 14 but at each actuation of the line spacing handle or finger piece, said pawl will be swung rearward to engage with the ratchet wheel, the pawl and carrier thereafter turning coaxially with the platen and effecting a unit of line spacing turning movement of said platen.

When the platen is turned, the sleeve 18 turns in a tubular bearing member or sleeve 27 which is threaded through the right-hand end bar 9 of the platen frame. Said sleeve 27 is formed at its left-hand end with a flanged or shoulder portion 28, the outer end of which is forced tightly against the face of the end bar 9 by a nut 29 which maintains the sleeve in rigid relationship with the end bar. The left-hand end of the flanged portion 28 of the sleeve is contiguous to the outer face of the plate 16. Near its right-hand end said sleeve 27 is additionally supported in an enlargement or bearing eye 30 forming the terminal portion of an angular bracket or supporting member 31 which is arranged parallel with the right-hand end bar 9 but outside the truck and is rigidly secured to said end bar. To secure or fix the bracket 31 to the end bar, said bracket at its upper rear end portion is provided with an angular extension 32 which receives screws 33 that are threaded into the end bar 9. At its lower end, said bracket is provided with a boss or hub 34 which receives a long shoulder screw 35 that is threaded into the lower portion of the end bar 9, a washer 36 being interposed between the inner end of the boss

and the adjacent link 12. The upper stop screw 7 is screwed down against the sleeve 27 and locked by its nut 8. Thus the sleeve is tightly engaged by the two opposing stop screws 7 so as to prevent shifting movements of the platen frame, the platen frame being thus held in rigid relationship with the truck, the stop screws at the opposite end of the platen frame being similarly set to prevent shifting movements. Of course, it is to be understood that the present invention is readily applicable to machines employing shiftable platens. It will further be understood that when the platen is turned by the line spacing devices, the sleeve 18 and the shaft or axle portion 19 will revolve together inside the stationary sleeve or bearing 27.

In addition to the platen turning or rotating devices comprising the regular line spacing mechanism and the finger wheel 20, novel platen sweeping means are provided for continuously rotating the platen, or "sweeping" it as is frequently termed, both forward and backward. Said means comprise generally a handle or crank arm which is concentric with the platen but normally disconnected therefrom and which controls pawl and ratchet devices for rotating the platen in connection with novel stop devices for variably limiting the extent of rotation both forward and backward. Most of the devices comprised in the said means are mounted on that portion of the sleeve 18 which extends outward or rightward beyond the bracket 31. Supported loosely on said sleeve 18 adjacent to the outer or right-hand face of the bracket 31 is a washer or spacing annulus 37. Contiguous to the washer 37 is a rotary stop member 38 comprising an annular portion 39 from which projects a stop lug 40 and further comprising a radial arm 41 from which projects a lateral pin 42 reduced slightly at its end. The annular portion 39 is formed with a hole indicated at 43 which bears loosely on the sleeve 27. On the sleeve rightward from the stop member 38 is a friction spring or spider of spring metal which is adapted to exert friction on various devices subsequently to be described that are mounted on the sleeve to the right of said friction spring. The latter comprises an annular portion 44 from which radiate spring fingers 45. These are adapted to bear against the left-hand face of a rotary cam member 46 having two circular faces or dwell portions 47 and 48 of different radii connected by a cam or incline 49, said member being provided with an arm 50 having a notch indicated at 51 and being formed centrally with a hole 52 to fit over the sleeve 27. Next succeeding the cam member on the sleeve is a wheel or disk 53 which combines the functions of a stop controller and pawl controller. Said

wheel is formed centrally with a hole 54 to fit over the sleeve. The periphery of said wheel is formed with a series of square teeth 55 alternating with notches 56. Adjacent to the notched or toothed portion 55, 56, the periphery of the wheel 53 is smooth, the smooth surface however being interrupted by a slot or depression indicated at 57, the slot terminating in opposite parallel faces or walls 58 and 59. The outer or right-hand face of the wheel or disk 53 is formed with a circular groove or depression 60 having a closed end 61, the opposite end running into an open mouth 62 having opposite faces or walls 63 and 64. To the right of the notched wheel 53 is mounted a ratchet wheel 65 having preferably the same number of teeth as the line spacing ratchet wheel 14. The wheel 65 is provided with a rightwardly extending collar or hub portion 66 which is interiorly threaded and is also split at opposite sides as indicated at 67. The threaded hub 66 is screwed on the outer end of the sleeve 18 which is exteriorly threaded at 27^a to co-operate with the interior threads of the split hub 66. Mounted loosely on said hub contiguous to the ratchet wheel 65 is an arm 68 which is formed with a hole 69 to fit over the hub 66, said arm extending radially outward and carrying near its outer end a headed shoulder screw 70 which is secured in place by a check-nut 71 and provides a pivotal support for an adjustable stop member 72 having a tooth 73 adapted to fit in the notches 56 of the wheel 53, said pivoted stop 72 being provided with a flat spring 74 which tends normally to maintain the tooth 73 locked or engaged in one of the notches, thereby locking the stop 72 to the wheel 53. A handle or finger piece 75 projects outward from the stop 72 at one side of its pivot and may be manipulated to turn the stop 72 on said pivot to withdraw the tooth 73 from interlocking engagement, freeing the stop 72 and the arm or carrier 68 so that they may be rotated to re-locate or re-adjust the stop. Mounted to bear loosely on the hub 66 of the ratchet wheel 65 is a crank, sweep or rotary arm 76 provided with a laterally extending hub portion 77 bored out as indicated at 77^a to fit over the hub 66. At its upper end said crank is provided with a rightwardly extending finger piece or handle 78. Also mounted on the hub 66 to the right of the crank is a securing device in the form of a collar 79 having a central opening or hole 80 and a dividing cut or split 81. The split is bridged by a headed screw 82 which carries on its projecting end a nut 83. The collar 79 serves as a clamp for forcing the split hub 66 to maintain a positive engagement with the sleeve 27. By tightening the nut 83, the collar operates to draw the sides or parts of the split hub 66 closer together

and clamp them firmly against the sleeve 27^a so that when the ratchet wheel 65 is turned, the power will be positively transferred to the sleeve 27^a and the connected platen. Also the clamping device or collar 79 cooperates with the spring spider 44, 45 to hold intervening parts frictionally and prevent rattle or undue movement. The crank 76 has pivoted to it at 84 a pawl arm 85 provided with a tooth 86 that is in the plane of the ratchet wheel 65 but is normally separated or disconnected therefrom. The tail 87 of the pawl is adapted to co-operate with the lateral pin 88 on the crank 76. Near the free end of the pawl arm 85 is mounted a laterally projecting pin 89 on which is pivoted a roller 90, said roller being adapted to co-operate with the groove 60 in the wheel 53. The pawl arm or member 85 is loosely mounted on its pivot 84, movements of the pawl being positively controlled by the roller 90 in co-operation with the groove or track-way 60 and its mouth 62. Normally the pawl member is held as in Fig. 1, the roller 90 engaging in the mouth 62 and maintaining the pawl tooth 86 up out of engagement with the ratchet wheel 65, so that the platen may be turned either by the regular line spacing devices or by the finger wheels 20 independently of the pawl member 85 and the crank 76 and without disturbing the latter parts. The crank at this time remains in normal position, resting against the pin 42 of the stop member 38, which stop member is temporarily fixed in a pre-determined normal position as hereinafter described. The pin 88 on the crank engages in the notch 51 in the cam member 46, thus positively connecting the cam member and the crank and forcing the cam member 46 to participate in all of the movements of the crank. The reduced end of the pin or connecting device 42 projecting rightward from the stop member 38 engages in the notch or connecting device 57 in the wheel or disk 53, thus constantly or permanently connecting the two parts loosely or with a lost motion connection. Independent relative movement between the stop member 38 and the disk 53 is afforded to the extent of the slot 57, but after engagement of the pin 42 with either wall 58 or 59 of the slot, the two parts are forced to turn together by the connecting or engaging devices 42 and 57 and the arrest of one part effects the arrest of the other part. The stop member 38 is adapted to be arrested in both directions of its rotary travel by a projection or stop pin 91 which is fixed to and projects rightward from the bracket 31. Normally the stop member 38 is arrested in the Fig. 1 position by co-operation of the rear edge of the arm 41 with the frame stop 91. In said Fig. 1 the disk 53 is also shown at the limit of its backward rotation by reason of the engagement of the

wall 59 in the disk with the pin or stop 42 of the stop member. With the stop member in this position its pin is engaged by a locking device in the form of a spring-mounted hook 92 pivoted on a pivot screw 93 that is threaded into the bracket 31. Said hook is constantly urged forward on its pivot by a wire spring 94 coiled around the screw 93 between the bracket 31 and the inner face of the hook 92, the free end of the spring engaging with the back of the hook. Above its pivot the hook is off-set slightly towards the right so as to bring it in the same fore-and-aft plane as the cam member 46, said hook being provided with a rounded projection or nose 92^a which is contactive with the curved or arcuate dwells 47 and 48 and the cam 49. Through these faces or parts the cam member is adapted automatically to control the hook so as to throw it into and out of engagement with the pin 42. When the disengageable hook is engaged with the pin, the stop member 38 is locked or prevented from turning forward on its axis, the nose 92^a at this time being engaged with the dwell 47 which is the curve of lesser radius.

Let it be assumed that the stop 72 be adjusted with its tooth 73 engaged, say, with the ninth notch 56 of the wheel or disk 53 which is an adjustment of the stop that is suitable for a depth of heading equivalent to somewhat less than a complete revolution of the platen. With the parts as in Fig. 1 it may further be assumed that a bill sheet has just been written and withdrawn, its entries having been duplicated on the underlying record sheet which remains in the machine. For the purpose of turning the platen 13 continuously backward and causing it through co-operation with the feed or pressure rollers 15 to retract the record sheet to a position where a fresh bill sheet may be introduced at the back of the machine in proper relationship with said record sheet, the operator pulls forward the handle or finger piece 78, turning the crank or rotary arm 76 in counter-clockwise direction until it is arrested. During the initial stage of movement the crank pin 88 acting on the cam member 46 will turn it forward from the Fig. 1 to the Fig. 2 position, the dwell surface 47 riding under the nose 92^a without disturbing the hook 92 which remains engaged with the pin 42 on the stop member 38 preventing forward movement of said stop member. The wheel or disk 53, however, is free to turn and will be moved, as the result of friction primarily, to the Fig. 2 position, bringing the wall 58 of the slot 57 into contact with the pin 42, thus temporarily arresting the disk 53. It will be understood that the disk as it turns carries with it the rotary carrier 68 and the stop 72 interlocked with the disk in predetermined position. During this movement, the rela-

tionship of the roller 90 with the mouth 62 of the groove 60 is not disturbed or altered, but when the disk 53 is temporarily arrested as described, the roller moving forward under the impulse of the crank will be pressed against the forward wall 63 of the mouth 62 and will be thereby cammed downward into the groove 60, forcing the pawl tooth 86 to engage with the ratchet wheel 65. Thereafter during the subsequent rotation of the crank 76, the pawl tooth will be positively maintained in engagement with the ratchet wheel by reason of the co-operation of the roller 90 with the circular trackway 60. The crank is thus positively connected with the ratchet wheel which is rigidly related to the platen, so that from this stage onward the impulse of the crank 76 is communicated to the platen, turning it as the crank turns. It is to be understood, however, that during the initial stage of movement from the Fig. 1 to the Fig. 2 position while the disk 53 is turning relatively to the stop member 38, the platen will remain unaffected. This initial stage of movement of the crank without affecting the platen is equivalent to substantially two units of line space distance. The initial stage of movement from the Fig. 1 to the Fig. 2 position brings the cam face 49 into contact with the underside of the nose 92^a so that a further pull communicated to the crank 76 from the handle 78 and thence transmitted through the crank pin 88 to the cam member 46 will cause the cam face 49 acting against the nose 92^a to force the hook 92 to turn rearward on its pivot 93 against the tension of its spring 94. This movement of the pawl automatically unlocks or frees the pin 42 releasing the stop member 38. As the movement of the parts continues, the dwell face 48 will be brought into co-operation with the nose 92^a, the radius of this face being such that the hook 92 will be held back out of operative position during the remainder of the backward turning movement. The stop member 38 being now unlocked will be free to be turned by the disk or wheel 53, the wall 58 engaging with the pin 42 of the stop member and forcing it ahead. This movement of the parts will continue until the lug 40 of the stop member is brought into contact with the underside of the frame stop or pin 91 as shown in Fig. 3. The stop member is thus positively arrested and its pin 42 being held against movement will consequently positively arrest the disk 53. The adjustable stop 72 is thus held against further turning movement being finally arrested in the Fig. 3 position. It will be observed from this figure that relatively unimportant changes in the relationship between the pawl 85 and the disk 53 and stop 72 take place in passing from the Figure 2 to the Figure 3 posi-

tion. However, after the disk and the stop have been arrested as in Fig. 3, further turning of the crank 76 thereafter will force the pawl 85 ahead, causing its roller 90 to travel 5 along the groove in the now motionless trackway 60 until the final arrest of the crank, pawl, and platen takes places, due to the contact of the front face of the pawl with the rear or contact face of the stop 72 10 as shown in Fig. 4.

As a result of this backward turning movement of the platen, the record sheet has been retracted to a predetermined extent. A new bill sheet is next inserted and the described operations are reversed, the handle 78 and the crank 76 being pulled or turned forward. During the first stage of the return or forward movement all the parts will turn together without change in their relationship, after the lost motion between the wheel or disk 53 and the stop member 38 is taken up. In other words, the stop member initially will remain motionless until the wall 59 of the slot in the disk 25 engages with the pin 42 after which all the parts will turn together until the stop member is arrested by the arm 41 engaging the stationary frame stop or pin 91. The arrest of the stop member likewise results in the arrest of the disk 53, and the parts are so timed that the cam face 49 of the cam 46 30 will run down over the nose 92 permitting the hook 92 to re-engage with the pin 42. The disk 53 having been arrested as described, the further turning of the crank 76 and the platen will cause the roller 90 to move along through the grooved track-way 60 until said roller contacts with the rear wall 64 of the mouth 62, said wall acting as 35 a cam to lift the pawl 85 and disconnect its tooth 86 from the ratchet wheel 65. This disconnection however will not take place until after the pawl and ratchet have turned the platen on the forward sweep through 40 two more units of line space distance than it was turned during the backward sweep, this additional movement being due to the fact that there is no lost motion of the pawl relative to the ratchet wheel, as there was 45 at the beginning of the backward sweep. The result is that the record sheet will be advanced automatically to space between the last line of the preceding bill sheet and the first line of the newly entered bill sheet. 50

By the described operations the new bill sheet has been advanced continuously to a predetermined extent and brought into position to receive the first line of writing, while the underlying record sheet has likewise been advanced and in position to receive the next line of writing, two units of line space distance under the last preceding line of writing. Next, the operator actuates the usual printing instrumentalities 55 (not shown), the imprints being made on

the bill sheet through the usual ribbon and being duplicated on the underlying record sheet through an interleaved carbon sheet. The bill, the record and the carbon may be advanced from line to line by actuating the 70 line space mechanism, the crank or rotary arm 76 and the novel platen sweep mechanism generally remaining unaffected by such line spacing actuations, although of course the ratchet wheel 65 will turn with the 75 platen. The bill having been written or filled in is withdrawn and then the platen sweep mechanism is operated to retract the record sheet to a predetermined extent after which a fresh bill sheet is inserted and continuously advanced along with the record sheet in the described manner. The mechanism is rapid and efficient in operation and may be employed in the manner described to turn out in a comparatively short time a 80 large number of typewritten bills, the entries being duplicated on a record sheet or sheets and properly condensed or spaced apart.

It will be understood that the extent of 85 continuous turning movement communicated to the platen by the crank before the parts are arrested by the stop devices may be varied in accordance with the depth of the heading on the bill sheet by adjustment 90 of the stop 72. The range of adjustment of the stop is of course determined by the series of teeth 55 in the disk 53, said disk being in effect a circular rack along which the stop 72 may be adjustably set. Said stop 95 when in the uppermost notch 56 in the disk viewed in the Fig. 1 position, is set to give the least extent of movement or sweep, while when said stop is set at the opposite end of the rack or series of teeth it will afford the greatest extent of sweeping movement or continuous rotation of the platen. 100

Furthermore, it is to be understood, that while the mechanism is particularly adapted for use in condensed record work involving record or ledger sheets and statements or bill sheets in the manner above outlined, nevertheless the employment of the mechanism is not restricted to this particular use but it is also adapted to other styles of 110 typewritten work in which continuous rotary movements of the platen as distinguished from step-by-step line spacing movements are made use of. 115

What I claim as new and desire to secure 120 by Letters Patent is:—

1. In a typewriting machine, the combination of a platen, a finger piece, operative connections between said finger piece and said platen effective to move said platen when said finger piece is actuated, a stop effective to limit the movement of said platen in one direction when actuated by said finger piece, locking devices for normally locking 125 said stop against movement, and devices for 130

- 6 automatically rendering said locking devices ineffective.
2. In a typewriting machine, the combination of a platen, a finger piece, operative connections between said finger piece and said platen effective to move said platen when said finger piece is actuated, a stop effective to limit the movement of said platen in one direction when actuated by said finger piece, and locking devices for normally locking said stop against movement, said finger piece being effective to throw said locking devices out of use and to move said stop. 10
3. In a typewriting machine, the combination of a rotary platen, a platen rotator provided with a finger piece, operative connections between said rotator and said platen, and a stop for positively limiting movement of said platen by said rotator, said stop being normally locked against movement and being rendered ineffective automatically by said rotator. 15
4. In a typewriting machine, the combination of a rotary platen, a platen rotator provided with a finger piece, operative connections between said rotator and said platen, a rotary stop device for positively limiting movement of said platen by said rotator in one direction, a co-operative fixed stop, devices for locking said rotary stop normally against movement, and devices operative by said rotator to throw said locking devices out of use. 20
5. In a typewriting machine, the combination of a platen, a finger piece, operative connections between said finger piece and said platen effective to move said platen when said finger piece is actuated, and means for positively limiting the movements of said platen by said finger piece, said means comprising a rotary stop member, a co-operating frame-stop, a lock normally effective on said rotary stop member, and devices actuated by said finger piece for controlling said lock. 25
6. In a typewriting machine, the combination of a platen, a finger piece, operative connections between said finger piece and said platen effective to move said platen when said finger piece is actuated, and means for positively limiting the movements of said platen by said finger piece, said means comprising a rotary stop member, a co-operating frame-stop, a lock normally effective on said rotary stop member, and a rotary cam member operative by said finger piece to throw out said lock. 30
7. In a typewriting machine, the combination of a platen, a finger piece, operative connections between said finger piece and said platen effective to move said platen when said finger piece is actuated, and means for positively limiting the movements of said platen by said finger piece, said means comprising a rotary stop, a co-operating frame stop, a spring pressed hook normally engaging said rotary stop to lock it against movement, and a rotary cam actuated by said finger piece for throwing said hook out of action during movement of said finger piece in one direction, said cam permitting the hook to relock the rotary stop during movement of the finger piece in the opposite direction. 35
8. In platen sweep mechanism for typewriting machines, the combination of a rotary stop member having only a limited extent of rotary movement, a hook normally restraining said stop member from movement, and a rotary member operative from the platen sweep handle and provided with two circular dwell portions and an intervening cam portion, said portions being co-operative with said hook. 40
9. In a typewriting machine, the combination of a platen, a finger piece, operative connections between said finger piece and said platen, a rotary stop provided with a plurality of fixed projections, a frame stop co-operative with said projections to limit turning movements of said rotary stop, and a normally effective lock for said rotary stop. 45
10. In platen sweep mechanism for typewriting machines, stop devices for limiting continuous rotary movements of the platen, said devices comprising a pair of rotary stop members having a permanent lost motion connection. 50
11. In platen sweep mechanism for typewriting machines, stop devices for limiting continuous rotary movements of the platen, said devices comprising a pair of rotary stop members, and a pin and slot connection between said stop members permitting their limited relative movement. 55
12. In platen sweep mechanism for typewriting machines, stop devices for adjustably limiting continuous rotary movements of the platen, said devices comprising a pair of rotary stop members permanently connected together but capable of limited relative movement, and a stop adjustable on one of said stop members. 60
13. In platen sweep mechanism for typewriting machines, the combination with a platen and a platen sweep, of stop devices for limiting continuous rotary movements of the platen, said devices comprising a pair of rotary stop members permanently connected together but capable of limited relative movement, one of said stop members being formed with peripheral teeth, a stop carrier, a stop pivoted on said carrier and adjustable to engage with pre-determined ones of said teeth, and a second stop on the platen sweep itself co-operative with said adjustable stop. 65
14. In a typewriting machine, the combination with a platen and a platen sweep, 70
- 75
- 80
- 85
- 90
- 95
- 100
- 105
- 110
- 115
- 120
- 125
- 130

- of stop devices limiting continuous rotary movements of the platen, said devices comprising a pair of rotary stop members having a permanent lost motion connection, a pair of stops on one of said stop members, said pair having an unvarying relationship, a frame stop co-operative with said pair of stops, and a stop adjustable on the other of said stop members.
- 10 15. In a typewriting machine, the combination with a platen and a platen sweep, of devices for limiting continuous rotary movements of the platen, said devices comprising two rotary stop members, and means normally preventing movement of one of said members, said means normally affording restricted rotary movements of the other stop member.
- 15 16. In platen sweep mechanism for typewriting machines, the combination of stop devices for limiting continuous rotary movements of the platen, said devices comprising two rotary stop members, a hook normally engaging one only of said stop members, and connecting devices on the stop members co-operating to afford limited movement of the disengaged stop member.
- 20 17. In platen sweep mechanism for typewriting machines, the combination of stop devices for limiting continuous rotary movements of the platen, said devices comprising two rotary stop members, a hook normally engaging one only of said stop members, connecting devices on the stop members co-operating to afford limited movement of the disengaged stop member, and means acting automatically on said hook to release both of said stop members.
- 25 18. In a typewriting machine, the combination with a platen and a platen sweep, of stop devices for limiting continuous rotary movements of the platen, said devices comprising two rotary stop members, a pin on one of said stop members constantly engaging a slot in the other of said stop members, and a disengageable hook normally engaging said pin.
- 30 19. In a typewriting machine, the combination with a platen and a platen sweep, of stop devices for limiting continuous rotary movements of the platen, said devices comprising two rotary stop members, a pin on one of said stop members constantly engaging a slot in the other of said stop members, a disengageable hook normally engaging said pin, and means for disengaging said hook from said pin.
- 35 20. In a typewriting machine, the combination with a platen and a platen sweep, of stop devices for limiting continuous rotary movements of the platen, said devices comprising two rotary stop members, a pin on one of said stop members constantly engaging a slot in the other of said stop members, a disengageable hook normally engag-
- ing said pin, and a rotary cam operative from the sweep handle to release said hook from said pin.
- 40 21. In a typewriting machine, the combination with a platen and a platen sweep, of stop devices for limiting continuous rotary movements of the platen, said devices comprising two rotary stop members, a pin on one of said stop members constantly engaging a slot in the other of said stop members, a disengageable hook normally engaging said pin, a spring for said hook, a rotary cam operative from the sweep handle to release said hook from said pin, a rotary member interposed between said stop members and controlled from the platen sweep handle, said rotary member being provided with two dwell portions and a cam portion, said portions co-operating with said hook automatically to control it in conjunction with the hook spring.
- 45 22. In a typewriting machine, the combination of a rotary platen, a ratchet wheel connected to the platen, a normally disengaged pawl co-operative with said ratchet wheel, a rotary platen sweep arm on which said pawl is pivoted, devices for limiting continuous rotary or sweeping movement of the platen under the impulse of said pawl and ratchet, said devices comprising a pair of rotary stop members having a permanent lost motion connection, and means on one of said stop members co-operating with said pawl to maintain it positively engaged with the ratchet wheel as the platen is continuously rotated.
- 50 23. In a typewriting machine, the combination of a rotary platen, a ratchet wheel connected to the platen, a normally disengaged pawl co-operative with the ratchet wheel, a rotary platen sweep arm on which said pawl is pivoted, devices for limiting continuous rotary movement of the platen under the impulse of said pawl and ratchet, said devices comprising a pair of rotary stop members, a pin and slot connection between said stop members permitting limited relative movements thereof, a circular trackway in one of said stop members, and a pin on said pawl engageable with said trackway to maintain positive engagement between said pawl and said ratchet wheel during continuous back and forth rotary sweeping movements of said platen.
- 55 24. In a typewriting machine, the combination of a rotary platen, a ratchet wheel connected to the platen, a normally disengaged pawl co-operative with the ratchet wheel, a rotary crank having a finger piece and arm on which said pawl is pivoted, devices for limiting continuous rotary movement of the platen under the impulse of said pawl and ratchet, said devices comprising a pair of rotary stop members per-
- 60 manently connected together but capable of

limiting rotary movement, one of said stop members being formed with peripheral teeth, an adjustable stop co-operative with said teeth, a circular groove in said toothed stop member, and a pin carried by said pawl engageable with said groove.

25. In a typewriting machine, the combination of a rotary platen, a ratchet wheel connected to the platen, a normally disengaged pawl co-operative with the ratchet wheel, a rotary hand operated sweep on which said pawl is pivoted, devices for limiting continuous rotary movement of the platen under the impulse of said pawl and ratchet, said devices comprising two stop members, a hook normally engaging one only of said stop members, devices on the stop members co-operating to afford limited relative movement of the stop members, a circular groove in said disengaged stop member, a cam operative by said rotary sweep to disengage said hook, and a pin on said pawl co-operative with said groove.

26. In a typewriting machine, the combination of a platen frame, a platen provided with a stub shaft projecting from its end, and a second stub shaft disconnectibly connected with the first stub shaft and provided with a platen finger wheel operative to move both of said shafts.

27. In a typewriting machine, the combination of a platen frame, a platen provided with an outwardly extending stub shaft, and a second stub shaft supported in the platen frame and provided with a finger wheel, the adjacent ends of said stub shafts being detachably connected by tongue and slot.

Signed at the borough of Manhattan, city of New York, in the county of New York and State of New York, this 2nd day of October, A. D. 1923.

FREDERICK A. HART.
